UNITED STATES PATENT OFFICE

142,850

DESIGN FOR A COMBINED DESK AND BLACKBOARD

Samuel H. Geffner, New York, N. Y.

Application December 16, 1944, Serial No. 116,930

Term of patent 7 years

(Cl. D33—7)

To all whom it may concern:

Be it known that I, Samuel H. Geffner, a citizen of the United States of America, residing in city of New York, county of New York, and State of New York, have invented a new, original, and ornamental Design for a Combined Desk and Blackboard, of which the following is a specification, reference being had to the accompanying drawing, forming part thereof.

Fig. 1 is a perspective view of a combined desk and blackboard showing my new design.

Fig. 2 is a perspective view in open position illustrating the blackboard.

Fig. 3 is a perspective view in open position illustrating the blackboard in extended position.

I claim:

The ornamental design for a combined desk and blackboard, substantially as shown.

SAMUEL H. GEFFNER.
